United States Patent

Des. 237,317
Patented Oct. 21, 1975

237,317

TEST KIT TRAY

Edward Nowakowski, Chicago, and Harry James Pappas,
Hinsdale, Ill., assignors to Miles Laboratories, Inc.,
Elkhart, Ind.

Filed Mar. 4, 1974, Ser. No. 447,487

Term of patent 14 years

Int. Cl. D24—99

U.S. Cl. D83—1 U

FIG. 2

FIG. 3

FIG. 1 is an isometric view of a test kit tray showing our new design.

FIG. 2 is a side elevation view of the tray taken along line 2—2 of FIG. 1.

FIG. 3 is a top plan view of the tray of FIG. 1.

We claim:

The ornamental design for a test kit tray, substantially as shown and described.
